(57) **CLAIM**

The ornamental design for a portable water filter, as shown and described.

DESCRIPTION

FIG. 1, is a front top left perspective view of the portable water filter, showing my new design;

FIG. 2, is a bottom left perspective view thereof;

FIG. 3, is a front elevation view thereof;

FIG. 4, is a rear elevation view thereof;

FIG. 5, is a top plan view thereof;

FIG. 6, is a bottom plan view thereof;

FIG. 7, is a left side elevation view thereof, the right side being a mirror image of FIG. 7; and,

FIG. 8, is an exploded view thereof.

The elements shown in broken lines in FIGS. 1-8 are included for the purpose of illustrating environment and form no part of the claimed design.

The parallel surface shading lines on the claimed portion are provided only to indicate the character and/or any contour or curvature of the surfaces. They do not indicate color, texture, markings that actually exist thereon, indicia, graphic representations, surface treatment, or any other ornamentation applied to the article.
